[57] ABSTRACT

A cam loosely mounted on a constantly rotating drive shaft is normally held stationary independently of the drive shaft rotation and is permitted to rotate through a prescribed angle upon depression of the shift key or shift lock key of the typewriter. This rotary motion of cam is translated into the upward displacement of the typewriter carriage via a linkage coupled to a rail slidably supporting the carriage thereon. The linkage is further operatively coupled to a toggle joint mechanism adapted to assist the up-and-down motion of the carriage.

FIG. 5

FIG. 6

**CARRIAGE SHIFT MECHANISM FOR AN
ELECTRIC TYPEWRITER**

BACKGROUND OF THE INVENTION

This invention relates generally to typewriters and in particular to electric typewriters. More specifically, the invention is directed to a mechanism for shifting the carriage, and therefore the platen, of an electric typewriter for the purpose of selective printing of capitals and small letters and of other characters or symbols on the upper and lower halves of the respective keys.

It is well known that in the electric typewriters of this class, an electric motor drive is utilized to power the typing stroke, the carriage reciprocation, and the carriage shifting. Since each of these functions is performed by clutching the proper linkage to a drive shaft held in constant rotation by the motor, it is necessary, for longer typewriter life and less operator fatigue, to minimize the load imposed on the drive shaft and the resistance offered by the keys. Much effort has indeed been expended industrially to this end. However, in view of the current state of the art, at least the carriage shift mechanism seems to be still in need of further refinement to be of true practical utility as it involves the greatest application of mechanical force.

SUMMARY OF THE INVENTION

It is, therefore, an object of this invention to provide a novel and improved carriage shift mechanism for an electric typewriter whereby the carriage can be shifted positively with minimum application of finger pressure to a key, and with no undue load imposed upon the constantly rotating drive shaft of the typewriter.

Another object of the invention is to provide a carriage shift mechanism of extremely simplified and inexpensive construction which can be easily incorporated in electric typewriters of known configuration.

With these objects in view and the other objects hereinafter set forth, this invention provides, in a typewriter of the class having a constantly rotating drive shaft, a carriage shift mechanism which includes a cam loosely mounted on the drive shaft and normally held stationary independently of the rotation of the drive shaft. When actuated by the shift key means of the typewriter, however, the cam rotates with the drive shaft through a prescribed angle thereby actuating cam follower means at one end of linkage means adapted to impart up-and-down motion to the carriage. The linkage means is connected at the other end to a toggle joint mechanism, the operation of which is initiated by the linkage means, to help the same impart up-and-down motion to the carriage. Hence the shifting of the carriage can be accomplished if there is sufficient mechanical force produced to cause the two levers of the toggle joint to turn past their straight-line position.

The features which are believed to be novel and characteristic of this invention are set forth with particularity in the appended claims. The invention itself, however, both as to its configuration and mode of operation, together with the further objects and advantages thereof, will be best understood from the following description taken in conjunction with the accompanying drawing which illustrates, by way of example only, a preferred embodiment of the invention and in which like reference characters denote like parts in the several views.

BRIEF DESCRIPTION OF THE DRAWING

In the drawing:

FIG. 1 is a partly broken away perspective view of a carriage shift mechanism constructed in accordance with the principles of this invention;

FIG. 2 is a side elevational view showing the essential parts of the mechanism shown in FIG. 1;

FIG. 3 is an exploded perspective view showing the manner in which a cam is mounted on the drive shaft of the typewriter in the arrangement of FIG. 1;

FIG. 4 is a side elevational view showing how the cam is held stationary in its normal position on the drive shaft;

FIG. 5 is a similar view showing how the cam is caused to rotate with the drive shaft through a prescribed angle to its operative position upon depression of the shift key or shift lock key of the typewriter; and

FIG. 6 is an exploded perspective view showing the manner in which the drive shaft is coupled to a source of rotary power such as an electric motor in the arrangement of FIG. 1.

DETAILED DESCRIPTION

25 With particular to FIG. 1, reference numeral 1 designates a drive shaft which is in constant rotation to power the sequential impression of characters from a group of type arranged on separate rods (not shown) or other means in accordance with the prior art. The 30 constant rotation of the drive shaft 1 is further utilized according to this invention to effect a shift in the position of a carriage 2 and hence in the printing position of the typefaces against the paper for selection between capitals and small letters or between other characters or symbols on the upper and lower halves of the respective keys (not shown) of the typewriter.

For such shifting of the position of the carriage 2, the drive shaft 1 has a cam 7 loosely mounted on one end thereof to impart the desired up-and-down motion to the carriage 2 via linkage means comprising a pair of levers 3 and 4, a bell crank 5 and a link 6. Although not shown in the drawing, it is assumed that the drive shaft 1 is coupled to a source of rotary power such as an electric motor via a pulley 8 and an endless belt 9, the pulley 8 being coupled to the drive shaft 1 via means adapted to absorb any undue resistance offered to its rotation, as will hereinafter be set forth in more detail in connection with FIG. 6.

50 As seen more clearly in FIG. 2, the aforesaid pair of levers 3 and 4 are in scissorlike arrangement, both being turnably supported by a shaft 10 at their crossing point. These levers 3 and 4 carry cam followers in the form of rollers 11 and 12 on their respective ends 3a and 4a disposed opposite the cam 7, and the other ends 3b and 4b of the respective levers 4,5 are yieldably urged against each other as by means of a helical tension spring 13. These contacting ends 3b and 4b are partly recessed correspondingly to define a slot 15 therebetween. Slidably received in this slot 15 is a pin 14 fixed to one end of the bell crank 5 which is turnably supported, at the apex of the angle formed by its two arms, by a shaft 18 fixed in an elongate stationary member 17 secured to the frame 16 (FIG. 1), of the typewriter. The other end of the bell crank 5 is turnably coupled to one end of the link 6 by a pin or shaft 19.

A carriage rail 21 is secured to the link 6 at or adjacent the other end thereof and the rail 21 is adapted to

impart up-and-down motion directly to the carriage 2 supporting a platen or cylinder 20 in the usual manner. The link 6 further carries an adjustable stop 22 intermediate both ends thereof, the stop 22 being adapted to make contact with a bend portion 23 of the stationary member 17 to determine the lower limit of the swinging motion of the link 6. Another adjustable stop 24 is supported by the stationary member 17 to determine the upper limit of the swinging motion of the link 6.

The said other end of the link 6 secured to the carriage rail 21 is further coupled by a pin or shaft 25 to one end of a lever 27 which is turnably supported by a shaft 26 at a point intermediate the two ends thereof. The other end of lever 27 is coupled by a pin or shaft 30 to one end of a lever 29 having a helical compression spring 28 wound somewhat loosely thereon. A toggle joint mechanism is thus formed by the levers 27 and 29.

It will be seen from FIGS. 1 and 2 that the helical compression spring 28 is supported between an annular member 29a loosely fitted over the lower end portion of the lever 29 and an abutment 29b formed at its upper end. The lever 29 is further slotted longitudinally at its lower end portion, as indicated at 29c, and a pin 32 on the frame 16 is slidably received in slot 29c in contact with the annular member 29a thereby holding the same on the lever 29 against the force of the spring 28. A helical tension spring 33 is stretched between the said other end of the link 6 and the frame 16, for purposes hereinafter made apparent.

As illustrated in detail in FIG. 3, the cam 7 loosely mounted on one end of the drive shaft 1 has a radial projection 7a and a slit 7b, the latter being adapted to engage one end 34a of a helical spring 34 fitted over the drive shaft 1. The other end 34b of the spring 34 extends radially outwardly with respect to the drive shaft 1 and, as seen in FIGS. 4 and 5, is thus adapted to engage either of the prongs 35a and 35b of a fork 35. It is important to note that the spring 34 is of such inside diameter that it is capable of simultaneous rotation with the drive shaft 1, and further that the spring 34 is coiled in a direction opposite the direction of rotation of the drive shaft 1 indicated by the arrow a in FIG. 3.

Referring again to FIG. 1, the fork 35 is supported by a shaft 36 fixed to the frame 16 so as to be swingable back and forth, or in directions normal to the drive shaft 1, and is further yieldably urged as by means of a helical spring 37 in such a way that its prong 35a will normally engage the end 34b of the spring 34. The fork 35 is coupled via a link 38 to one end of a shift lever 39 which is swingable on a shaft 40 and which carries a shift key 41 on the other, or forward, end thereof. A shift lock key 42 is provided adjacent the shift key 41 in accordance with the prior art. The shift lever 39 is provided with automatic return means in the form of a helical tension spring 43.

As best shown in FIG. 6, the aforesaid pulley 8 has an axial bore 44 therethrough adapted to receive a smaller diameter portion 1a of the drive shaft 1 with appropriate clearance. A lever 45 is mounted on the outside of the pulley 8 by receiving a screw threaded portion 1b of the drive shaft 1 in its rectangular aperture, and another lever 48 is mounted further on the outside of the lever 45 by loosely receiving the screw threaded portion 1b and by additionally receiving a stop pin 46 projecting laterally from the pulley 8 in its

rectangular aperture 47. A lock nut 49 is fitted over the screw threaded portion 1b to prevent detachment of the above listed parts from the drive shaft 1. A helical tension spring 50 is stretched between the levers 45 and 48, and a stop lug 45a is formed integrally with the lever 45 to engage the other lever 48 in such a way that the two levers 45 and 48 are normally held in their respective positions illustrated in FIG. 1. A collar 51 is also fitted over the drive shaft 1 on the inside of the pulley 8.

Proceeding to the description of operation of this preferred embodiment of the invention, it will be noted that FIG. 1 represents the normal or inoperative condition of the carriage shift mechanism, with the prong 35a of the fork 35 in engagement with the end 34b of the spring 34 as illustrated in FIG. 4. Since the spring 34 is wound around the drive shaft 1 in the opposite direction to that of its rotation as previously mentioned, the spring 34 is held stationary regardless of the rotation of the drive shaft 1 taking place in a direction tending to increase its diameter. The cam 7 is also held stationary on the rotating drive shaft 1, so that the spring 34 is now held unloaded.

It is assumed that while the spring 34 is thus held unloaded, the cam 7 engaging the end 34a of the spring in its slit 7b has its radial projection 7a directed upwardly as seen in FIG. 4. Thus, when the shift key 41 or shift lock key 42 is not depressed, the cam 7 is effective in raising the end 3a of the lever 3 via the roller 11, contrary to the condition represented in FIG. 2. The lever 3 thus caused to turn clockwise as seen in FIG. 2 causes corresponding turning of the other lever 4 via the spring 13, with the result that the bell crank 5 is caused to turn counterclockwise via the pin 14 slidably received in the slot 15 between the ends 3b and 4b of the two levers 3 and 4. The link 6 is then generally lowered to the position indicated in chain dotted lines in FIG. 2 thereby causing the lever 27 to turn counterclockwise. The lower portion of this lever 27 and the other lever 29 thus move past the straight-line position to their normal positions indicated by the chain dotted lines in FIG. 2. The spring 28 is of course compressed by this motion of the lever 29.

Discussed in the preceding two paragraphs is the normal condition of the carriage shift mechanism according to the invention, in which the carriage rail 21 and therefore the carriage 2 carrying the platen 2 thereon are held in lowered position, and in which the link 6 and associated structure are held in their respective inoperative positions in a stabilized manner by the action of the compression spring 28 and the balancing tension spring 33. The typist may now print the small letters and other characters on the lower halves of the respective keys.

Upon depression of the shift key 41 or of the shift lock key 42, as indicated by way of an example in FIG. 5 by a finger 52 on the shift key 41, the shift lever 39 turns counterclockwise on the shaft 40 to cause clockwise turning of the fork 35 via the link 38. The prong 35a of the fork 35 is now out of engagement with the end 34b of the spring 34, so that the spring 34 together with its radially extending end 34b becomes free to rotate simultaneously with the drive shaft 1. Since the other prong 35b of the fork 35 has been displaced toward the drive shaft 1 upon depression of the key 41 or 42, the end 34b of the spring 34 is thereby arrested

upon approximately 180° rotation around the drive shaft.

With its end 34b thus arrested by the prong 35b of the fork 35, the spring 34 is now held stationary on the drive shaft 1 rotating as aforesaid in the opposite direction to that in which the spring 34 is wound. Since the cam 7 engaging the end 34a of the spring 34 also rotates in step therewith, its radial projection 7a becomes effective to lower the end 4a of the lever 4 via the roll 12 thereby causing the levers 3 and 4 to turn counter-clockwise to the respective positions indicated in solid lines in FIG. 2. The bell crank 5 and the link 6 are further caused to assume their respective positions indicated in solid lines in FIG. 2.

This upward displacement of the link 6 is assisted by the toggle joint mechanism comprising the levers 27 and 29 as they move past their straight-line position by compressing the spring 28. The carriage 2 and therefore the platen 20 are thus shifted to their elevated position via the carriage rail 21 to permit the typist to print the capitals and other characters on the upper halves of the respective keys. It will be understood that the carriage 2 and associated linkages can be securely retained in their elevated position by the toggle joint mechanism now in the position indicated in solid lines 25 in FIG. 2 as long as the shift key 41 or shift lock key 42 is held depressed.

What is claimed is:

1. In a typewriter of the class having a source of rotary power, a drive shaft coupled to the source of rotary power to be thereby driven in constant rotation, and a carriage capable of being selectively moved between raised and lowered positions, a carriage shift mechanism comprising, in combination:

shift key means;

a cam mounted on the drive shaft to be rotatable relative to the drive shaft and normally held stationary independently of the rotation of said drive shaft; means actuated by said shift key means to permit said cam to undergo rotation through a prescribed angle together with said drive shaft;

cam follower means actuated by said cam upon its rotation through said prescribed angle;

linkage means actuated by said cam follower means to impart up-and-down motion to said carriage, 45

said linkage means comprising a pair of levers in scissor-like crossed arrangement pivotably connected at central parts thereof and having respective first ends located on opposite sides of said cam to form said cam follower means, said levers having 50 opposite second ends resiliently urged into contact
